UNITED STATES PATENT OFFICE.

AMARIAH W. JACKSON AND COURTLAND S. WHITE, OF CHICAGO, ILLINOIS;
SAID JACKSON ASSIGNOR TO CHARLES F. HUNT, OF SAME PLACE.

STEAM-ENGINE.

SPECIFICATION forming part of Letters Patent No. 276,970, dated May 1, 1883.

Application filed March 16, 1883. (Model.)

To all whom it may concern:

Be it known that we, AMARIAH W. JACKSON and COURTLAND S. WHITE, citizens of the United States, residing at Chicago, in the county of Cook and State of Illinois, have invented certain new and useful Improvements in Steam-Engines, of which the following is a specification, reference being had to the accompanying drawings.

10 This invention relates to certain improvements in that class of steam-engines known as "oscillating engines," and it has for its object to simplify and cheapen the construction of the same and produce a compact and smoothly-working engine, as more fully hereinafter specified. These objects we attain by the means illustrated in the accompanying drawings, in which—

Figure 1 represents a transverse vertical sectional view of our improved engine, taken on the line $x x$ of Fig. 2; and Fig. 2, a longitudinal sectional view of the engine, showing the valves in elevation.

The letter A indicates a metallic shell or casing of segmental shape, having at its bottom a semi-cylindrical seat, B, for the valves, and the hub on which the piston oscillates, as more fully hereinafter specified. Into the bottom of the said semi-cylindrical seat, near the ends, extend the induction-pipes C, and at each side of said induction-pipes are formed the eduction-ports D, as shown in Fig. 1 of the drawings. The casing is provided with suitable heads, E, which are secured to the flanges F at the ends of the casing by means of screw-bolts or otherwise. The heads are provided with journal-bearings for a shaft, G, which passes through the lower portion of the casing.

The letter H indicates a flat piston, which is cast with a cylindrical hub, I, through which the shaft passes, the said section being adapted to oscillate in the semi-cylindrical recess above mentioned. At each side of said section is located a cylindrical valve, K, the said valves being mounted loosely on the shaft and adapted to oscillate in the semi-cylindrical seat above mentioned. The said valves are provided with ports L M, and at the ends with recesses N, in

which are adapted to work the lugs P on the shaft G, for the purpose hereinafter set forth. 50 The heads of the casing are provided with annular recesses R, in which set the annular packing-rings S, through which the shaft passes, the said rings being held in place by means of the screws T. The piston has the 55 hub cast with it or is rigidly connected to the same, and the hub is keyed or otherwise securely fastened to the shaft, so as to turn it when the said piston is oscillated.

The operation of our invention is as follows: 60 The piston being in the position shown in Fig. 1, the steam is admitted through the induction-pipes C, and passes through the port M in the valves, causing the piston to travel to the left, forcing the air out through the port L 65 and eduction-port D at one side. When the piston has nearly completed its stroke the lugs on the shaft engage the recesses m' in the valves, causing the valves to shift so as to reverse the ports and cause the piston to travel in the 70 opposite direction. By attaching cranks to the shaft, connected by means of suitable pitmen to the cranks of a fly-wheel, a rotary motion suitable for imparting power to machinery may be obtained.

Having thus described our invention, what we claim, and desire to secure by Letters Patent, is—

The combination, in an engine, of the angular casing, having a semi-cylindrical seat, with 80 suitable induction-pipes and eduction-ports, a shaft to which is keyed a hub adapted to work in said seat, an oscillating piston cast with said hub, two partially-rotating valves provided with ports and recesses at their ends, 85 within which recesses set lugs on the shaft, whereby the valves are shifted, substantially as and for the purposes specified.

In testimony whereof we affix our signatures in presence of two witnesses.

AMARIAH W. JACKSON.
COURTLAND S. WHITE.

Witnesses:

HENRY C. STRONG,
JOHN F. FLOWER.
